UNITED STATES PATENT OFFICE.

GEORGE E. KING, OF NEWTON, MASSACHUSETTS, ASSIGNOR TO THE GAME-WELL FIRE-ALARM TELEGRAPH COMPANY, OF NEW YORK, N. Y.

DESIGN FOR A FRAME FOR TIME-STAMPS.

SPECIFICATION forming part of Design No. 33,708, dated December 11, 1900.

Application filed November 13, 1900. Serial No. 36,411. Term of patent 14 years.

To all whom it may concern:

Be it known that I, GEORGE E. KING, residing in Newton, county of Middlesex, and State of Massachusetts, have invented and produced a new and original Design for a Frame for Time-Stamp, of which the following is a specification, reference being made to the accompanying drawing, forming a part thereof.

10 The drawing shows in perspective my newly-designed frame for time-stamps.

15 *a* represents a substantially quadrangular base having an opening through it. *b b* represent a pair of side pieces projecting upright from said base, having recesses *c c* formed in

their front edges, shaped substantially as shown, and *d* represents a substantially quadrangular top plate surmounted on top of said upright side pieces *b b* and having a circular hole *d'* through it.

20

I claim—

The design for a frame for time-stamps herein shown and described.

In testimony whereof I have signed my name to this specification in the presence of 25 two subscribing witnesses.

GEORGE E. KING.
